UNITED STATES PATENT OFFICE

2,634,108

HEAT EXCHANGER

Henry F. Rohmann, Evansville, Ind., assignor to
Servel, Inc., New York, N. Y., a corporation of
Delaware

Application October 28, 1948, Serial No. 56,972

1 Claim. (Cl. 257—246)

1

The present invention relates to refrigeration and more particularly to a heat exchanger construction.

The heat exchanger of the present invention is particularly adapted for use in the absorption liquid circuit of absorption refrigeration systems of the type used in household refrigerators but is not necessarily limited to such use or even to use in an absorption type refrigeration system.

The object of the present invention is to provide a heat exchanger of improved construction which adapts it for economical manufacture. The improvement resides in forming a heat exchanger by merely telescoping the ends of intermediate tubes between the ends of concentric tubes and welding the joints therebetween. While the parts may be welded in any suitable manner, the invention also includes a method of fabrication by which the parts are welded into an integral structure by a single brazing operation.

The above objects will become more apparent from the following description and drawing in which like reference characters denote like parts throughout the several views. It is to be understood, however, that the drawing is for the purpose of illustration only and not a definition of the limits of the invention, reference being had for this purpose to the appended claim. In the drawing:

Fig. 1 is a diagrammatical view of an absorption refrigeration system incorporating the heat exchanger of the present invention;

Fig. 2 is a longitudinal sectional view of the ends of the heat exchanger showing intermediate tubes telescoped between the ends of inner and outer concentric tubes and welded together to seal the joints therebetween; and

Fig. 3 is a transverse sectional view taken on line 3—3 of Fig. 2 and showing the inner and outer chambers of the heat exchanger.

In the drawing, the heat exchanger of the present invention is shown embodied in an absorption refrigeration apparatus of a uniform pressure type utilizing a refrigerant, an absorbent and an auxiliary pressure equalizing gas. Apparatus of this type is well known and comprises a generator 5, a condenser 6, an evaporator 7, a gas heat exchanger 8, absorber 9 and liquid heat exchanger 10. The generator 5 has a flue 11 and a shell 12 surrounding the flue to provide a chamber 13 therebetween. The generator 5 is heated by a gas burner 14 which projects a flame into the flue 11 and refrigerant is expelled from absorption solution in the

2

chamber 13 by heat transmitted through the wall of the flue. Refrigerant vapor flows from the generator 5 through a conduit 15 connecting the upper end of chamber 13 to the upper end of the condenser 6. The condenser 6 is in the form of a pipe coil having a plurality of loops with spaced fins 16 thereon and the condenser is cooled by air flowing between the fins 16 and over the pipe coil. Refrigerant vapor 10 is condensed in the condenser 6 and flows from the bottom of the condenser to the top of the evaporator 7 through a conduit 17. The evaporator is illustrated in the form of a vertically arranged pipe coil and the refrigerant flows 15 from the top to the bottom by gravity.

Absorption liquid from which refrigerant has been expelled flows by gravity from the bottom of the chamber 13 of the generator 5 to the top of the absorber 9 in a path of flow comprising 20 a conduit 18, outer passage of the liquid heat exchanger 10 and conduit 19. The absorber also comprises a vertically arranged pipe coil having fins 20 and the absorption liquid weak in refrigerant flows by gravity through the absorber 25 and into an absorber pot 21 connected to its lower end. The absorption liquid absorbs refrigerant vapor as it flows through the absorber 9, as later explained in detail, and the absorber is cooled by air flowing between the fins 20 and over the pipe coil. Absorption liquid strong in refrigerant flows from the absorber pot 21 to the generator 5 in a path of flow comprising a conduit 22, inner passage of the heat exchanger 10, coil 23 surrounding the 30 lower end of the generator flue 11 and vapor lift tube 24 connected to the chamber 13 of the generator 5 adjacent its top. Thus, relatively cool absorption liquid flowing from the absorber pot 21 is heated by the relatively hot absorption solution flowing from the generator 5 in the heat exchanger 10 and solution in the coil 23 is heated by the flue 11 to expel refrigerant vapor therefrom and lift the solution to a higher level as it is delivered to the generator 5 to cause it 35 to flow by gravity through the absorption liquid circuit.

The liquid refrigerant evaporates in the evaporator 7 and diffuses into a gas such as hydrogen at partial pressure to produce a refrigerating effect in the insulated refrigerator cabinet 25. The pressure equalizing gas is introduced into the bottom of the evaporator from the outer passage 26 of the gas heat exchanger 8. The mixture of refrigerant vapor and pressure equalizing gas flows from the top of the evaporator 5 and then downwardly through the in-

50
55

inner passage 27 of the gas heat exchanger into the absorber pot 21. The mixture of refrigerant vapor and pressure equalizing gas then flows upwardly from the absorber pot 21 through the absorber 9 in a direction countercurrent to the flow of absorption solution. Due to the affinity of the refrigerant and absorbent the refrigerant vapor is absorbed into the absorption solution and the pressure equalizing gas flows from the top of the absorber into the outer passage 26 of the gas heat exchanger 8 to complete its cycle of operation. A pressure vessel 28 is also provided in the gas circuit which is connected between the outlet from the condenser and the inner passage 27 of the gas heat exchanger 8 for regulating the pressure in the system in accordance with changes in operating conditions as well understood in the art.

In accordance with the present invention, the liquid heat exchanger 10 comprises an inner tube 30 and an outer tube 31 with the ends 32 and 33 of conduit 22 and coil 23, respectively, telescoped therebetween as most clearly shown in Fig. 2. Preferably, the inner tube 30 is slightly longer than the outer tube 31 and the ends 32 and 33, constituting intermediate tubes, extend into the outer tube 31 for a short distance. Thus, the inner tube 30, outer tube 31 and intermediate tubes 32 and 33 overlap each other at each end of the heat exchanger 10 and the intermediate tubes have substantially the same inside and outside diameters as the outside and inside diameters of the inner and outer tubes, respectively, so as to provide a close fit between the parts. Suitable inlet and outlet ports 34 and 35 are provided at opposite ends of the outer tube 31 for receiving the ends of conduits 18 and 19, respectively.

In its broadest aspect the invention comprises joining the ends of the inner tube 30, outer tube 31 and intermediate tubes 32 and 33 in any suitable manner, such as welding, brazing or soldering, to connect the parts into an integral structure and seal the joints therebetween. Preferably, however, the tubes of iron or steel are all joined by a single brazing operation. For this purpose the parts are first assembled by telescoping the intermediate tube 32, either as an integral part of conduit 22 or as a nipple to be later connected to the conduit, between the inner and outer tubes 30 and 31 at one end and telescoping the intermediate tube 33, either as an integral or separate part of coil 23, between the inner and outer tubes at the opposite end. A eutectic iron phosphide brazing material as described in the co-pending application for United States Letters Patent of Robert S. Taylor et al., Serial No. 660,126, filed April 6, 1946, now Patent No. 2,487,001, is then applied to each joint. The brazing material may be applied as a paste of powdered alloy mixed with a binder or as briquettes of compacted powdered alloy or as a solid metal. The assembly is then heated to the melting temperature of the brazing material which flows by capillary action between the parts to completely seal the joints J as illustrated in Fig. 2. Joints J of iron phosphide alloy have been found to be as strong as the iron and steel tubes which they bond but the alloy is quite brittle and is apt to crack if deformed as by bending. The heat exchanger construction of the present invention, however, reinforces the joints J so that any bending which might tend to crack the bonding material will occur at a place remote from the joints.

The heat exchanger 10 may be fabricated as a subassembly or may be fabricated with other elements such as the generator 5 and absorber 9 in a larger sub-assembly or the entire unit 5 may be fabricated by a single brazing operation. Thus, the heat exchanger 10 has a novel structure which facilitates assembly of the parts and the novel construction is particularly adapted for fabrication by a single brazing operation 10 as it provides a resulting structure which reinforces the brazed joints J.

In operation the inner tube 30 and intermediate tubes 32 and 33, constituting the ends of conduit 22 and coil 23, respectively, provide the 15 path of flow for absorption solution strong in refrigerant flowing from the absorber 9 toward the generator 5 and the annular chamber 36 between the inner and outer tubes 30 and 31, together with the conduits 18 and 19, provide the 20 path of flow for absorption solution weak in refrigerant flowing from the generator toward the absorber.

While a single form of the invention is herein illustrated and described it will be understood that modifications may be made in the construction and arrangement of parts without departing from the spirit or scope of the invention. For example, the term "tube" as used in the 25 specification and claim is intended to include oval or flattened tubes as well as cylindrical tubes. Therefore, without limitation in this respect, the invention is defined by the following 30 claim.

I claim:

35 A heat exchanger connected between elements in a refrigeration system comprising an inner section of ordinary tubing, an outer section of ordinary tubing, and intermediate sections of ordinary tubing telescoped between and extending from the inner and outer tubing sections at opposite ends thereof, the inner and outer peripheries of said intermediate tubing sections having a close fit with the inner and outer tubing sections to provide capillary spaces therebetween, a eutectic iron-phosphorus alloy in said capillary spaces to seal the joints, inlet and outlet ports adjacent the opposite ends of the outer tubing section, the interior of the inner tubing section providing one path of flow and the annular chamber between the inner and outer sections providing a second path of flow in heat exchange with the first path of flow, and the intermediate tubing sections forming extensions of the path of flow through the inner tubing section and adapted to be connected to other elements of the 40 refrigeration system.
